UNITED STATES PATENT OFFICE.

JOHN E. BLAND AND EDWARD J. GILLIGAN, OF PAWTUCKET, RHODE ISLAND, ASSIGNORS OF ONE-HALF TO EDWARD W. McDUFF AND FRANK J. McDUFF, OF PAWTUCKET, RHODE ISLAND.

PROCESS OF BLEACHING YARN-COPS.

SPECIFICATION forming part of Letters Patent No. 739,751, dated September 22, 1903.

Application filed November 8, 1902. Serial No. 130,612. (No specimens.)

To all whom it may concern:

Be it known that we, JOHN E. BLAND and EDWARD J. GILLIGAN, citizens of the United States, residing at the city of Pawtucket, in the county of Providence and State of Rhode Island, have invented a certain new and useful Improvement in Processes of Bleaching Yarn-Cops, of which the following is a specification.

10 This process relates to the bleaching of cotton-yarn cops, whereby the cotton yarn in the cops is thoroughly treated by gravitating liquid; and the object of this treatment is to simplify the manner of bleaching the cops, 15 whereby the same can be handled in large quantities and dispensing with the costly mechanical appliances as required in the vacuum or other process heretofore employed.

In the accompanying drawings, Figure 1 is 20 a cop, the yarn of which is of a dull gray color, as received from the spinning frame or mule, to be treated by this process. Fig. 2 is an end view of the cop. Fig. 3 represents a tapered spindle which is inserted in 25 the opening of the cop to retain the shape of said opening while the yarn is being treated by this process. Fig. 4 illustrates the manner of packing the cops in a cloth bag, which is first placed in a wooden box of a rectangular shape, said bag having its upper edges 30 caught on pins inserted in the edges of the box, which pins serve to keep the bag open during the time of packing. Fig. 5 is a top plan of Fig. 4, showing the manner of placing the cops in the bag. Fig. 6 is a perspective view of a bag of cops as ready to receive 35 the process of bleaching. Fig. 7 is a view in central vertical section of the preparatory tank for the liquor. Fig. 8 is a view in central vertical section of the circular kier, the sour-tank, and the storage-tank for the acid, 40 respectively. Fig. 9 is a view in central vertical section of the bleaching-tank and the storage-tank, respectively, for chlorid of lime or bleaching liquor. Figs. 10, 11, and 12 show 45 the liquor passing through the cop, which has been turned so to expose three sides, respectively, during the period of receiving this process. Fig. 13 represents the finished white 50 yarn-cop complete.

The cops to be bleached by this process have each a spindle c' , as shown in Fig. 2, inserted through its opening c^2 for the purpose of retaining said opening after the cop has been bleached, and these cops are then 55 packed in a common cotton or linen cloth bag c^3 , which bag has been previously laid in a wooden box c^4 with its upper edges caught in pins c^5 , which hold said bag in place until filled with the cops, after which the mouth 60 of the bag c^3 is closed by stitching, as at c^6 in Fig. 6.

The process of bleaching the cops is as follows: The preparatory tank A, Fig. 7, is first filled with cold water from the pipe a , after 65 which the valve a' is shut off. Then caustic is added to bring the water in the tank up to 3° of Twaddell. Then steam from the pipe b , which connects with a boiler, (not shown,) boils the contents up to 210° Fahrenheit, after 70 which is added fifteen pounds of white chip-soap, and this mixture is boiled until all is dissolved, which takes about forty-five minutes.

The next step in the process: The kier B, 75 which is empty, is now packed with the bags of cops c , as in Fig. 6, each of which bags weighs seven pounds, and rest upon an iron grate d , located about twelve inches from the closed bottom of the kier, and the level 80 of these cops comes within six inches of the bottom of a perforated sieve e , which is next placed on the kier. Then the valve f' of the delivery-pipe f , which has connection with the preparatory tank A, is opened to allow the 85 boiling liquor to flow into the said sieve e and through its perforations e' , saturating the cops in the bags and dripping through the openings d of the grate d into the chamber g in the bottom of the kier, from whence 90 it returns again through the bags to its normal level, as indicated by the dotted line h , which by this time the said liquor has become reduced in temperature. The valve f' is then shut off and the top of the kier is covered with wooden planks i , after which the valve f^2 is opened to allow steam from the pipe f^3 , which has connection with the boiler, to penetrate the aforesaid liquor in the kier 95 and to cause the liquor to again boil. j is a 100

vomit-pipe which is secured to the grate d and extends centrally of the kier and directly over the outlet of the steam-pipe f^3 and the liquor and assisted by the steam in said pipe 5 f^3 is raised from the chamber g through said vomit-pipe, from whence it strikes against a deflector k , which is secured to the central plank, as shown, and causes the liquor to flow over upon the sieve e . This vomiting movement of the liquor is regulated by the said valve f^2 , so that the ebullition of the liquor is on a level of about two inches above the sieve e . The liquor being lifted from the bottom of the kier B up through the vomit-pipe j 10 flows through perforations of the sieve e and through the cops $c c$ in the bags over and over again for twelve hours, after which time the valve f^2 is closed and the valve l' is opened to allow the unused liquor to pass through 15 the waste or drainage pipe l .

The next step in the process: After the kier B has been emptied of the liquor cold water from the pipe m is run on the sieve e for one hour to cool off the bags and wash off 20 any impurities in the yarn. Then the plank covering $i i$ and sieve e are removed from the top of the kier, and the bags are next packed in a sour-tank C . Then a sieve e^2 is placed on top of said tank C , after which 25 power is applied to operate a rotary pump n to deliver a cold sulfuric-acid liquid (which is contained in a storage-tank D and of two degrees of strength) through the pipes o and o' and into the sieve e^2 and keeping the same 30 completely covered to a depth of about three inches as it drips through the sieve e^2 , through the bags of cops, through the openings d^2 of a tray d^3 , and into a chamber g' , from whence it passes through a discharge-pipe p , which 35 delivers this liquid again into the tank D , and this second operation is kept up for two hours. This second treatment of the cops $c c$ in the sour-tank C is to neutralize whatever caustic is left in the cops from the preparation 40 used in the kier, so to make the cops more susceptible to the bleaching properties of the next process, and thus make this second operation the foundation of the bleaching for the cops. Now after the cops are 45 thus prepared they are placed in the bleaching-tank E so that they lay in the same position as they were previously placed in the kier B and sour-tank C and corresponding to the position of cop having its side A' up 50 permanent, as seen in Fig. 10. Power is applied to a rotary pump n' to deliver chemic of chlorid of lime of one and a half degrees of strength, which is contained in a tank F , through the suction-pipe o^2 , from whence 55 it is forced by the said pump up through the pipe o^3 to be deposited on the sieve e^4 , and this sieve, which is covered to a depth of three inches of the chemic, is provided with perforations e^5 e^5 , through which the chemic 60 passes, through the side A' of the cops, through the openings d^4 of a tray d^5 , and into the

chamber g^2 , from whence it passes through the discharge-pipe p' , which delivers the chemic again into the tank F , and this operation is kept up for two hours, after which 70 the pump is stopped and the bags are now turned and placed in the said tank E so that the side B^2 of the cop is uppermost and corresponding to the position as illustrated in Fig. 11. The pump n' is again put in operation to deliver the said chemic from the tank F for another period of two hours. The pump is again stopped, and this time the bags are turned and placed in the said tank so the side C^3 of the cop is uppermost 75 and corresponding to the position as shown in Fig. 12. Then the same operation of delivering the said chemic is given for another period of two hours, after which the pump n' is stopped and the valve p^2 of the 80 discharge-pipe p' is closed and the valve q is opened. The valve m' is now opened to allow cold water to run from the pipe m^2 through the sieve e^4 and through the bags of cops and into the chamber g^2 , from whence it flows 85 through the drainage or waste pipe q' . This operation is kept up for one hour, and this process completes the bleaching. The alkali in the cops $c c$ must now be neutralized to prevent the yarn from being burned by the 90 chemic in the tank F . To do this, the bags are again placed in the sour-tank C so that the side A' , Fig. 10, of the cops is uppermost, and the same operation of delivering the cold acid from the tank D is put through for one 95 hour, after which the bags are again turned so that the side B^2 , Fig. 11, of the cops is uppermost, and the pump n is again run for another one hour, and this completes the 100 neutralization of the alkali. 105

From this description it will be understood that there are three turning positions of the cops in the process of bleaching in the chlorid-of-lime tank E and two turning of the cops in the sour-tank C in the last souring—one 110 side on the first souring after they are taken out of the kier B , and before they are put into the bleaching-tank E . After the process of the neutralization of the alkali the acid left in the cops has now to be neutralized, 115 and to do this the valve m^3 is opened to allow cold water from the pipe m^4 to run through the sieve e^2 and through the bags of cops to the drainage-pipe r , and this operation is kept up for one hour, after which they are 120 treated to a slight solution of sal-soda liquid on the same principle as the chemic in the sour-tank C and pumped for one and a half hours to make the neutralization complete. Finally the bags of cops are taken out of the 125 sour-tank C and placed in a hydraulic extractor-machine (not shown) which rotates at fifteen hundred revolutions per minute, and thus withdrawing all the water out of the cops, with the result that the yarn in each 130 and all is perfectly white, after which the cops are taken out of the bags and placed on

a wooden tray in a drying-room, and this completes the process.

We claim as a novel and useful invention and desire to secure by Letters Patent—

5 1. The herein-described process of treating textile material such as cotton and wool, yarn on cops and bobbins and the like, consisting in wrapping the material to be treated in filtering-bags, finely dividing the treating liquors, permitting them to drip on said material, and feed slowly through the same by gravity, substantially as described.

15 2. The herein-described process of bleaching textile material such as cotton and wool yarn on cops, bobbins and the like, consisting in placing the material to be treated in suitable filtering-bags, spraying treating liquors through a suitable perforated medium, permitting the said liquors to drip slowly upon the materials to be bleached, allowing the same to slowly fall by gravity therethrough, whereby the material may be thoroughly bleached throughout, and removing

said bleached material to a washing-vat, substantially as described.

25

3. The herein-described process of bleaching textile materials such as cotton and wool yarn on cops and bobbins, consisting in placing the material to be treated in suitable filtering-bags, directing the treating liquors to said material in a finely-divided state, allowing the said liquors to drip slowly upon the materials to be bleached and feed therethrough by gravity and intermittently reversing the said materials through presentation to the bleaching liquors whereby they may be thoroughly bleached and finally washing said materials, substantially as described.

35

In testimony whereof we affix our signatures in presence of two witnesses.
